UNITED STATES PATENT OFFICE

HUGH DONNELL, OF WEST REDDING, CONNECTICUT, ASSIGNOR TO STÜNZI SONS SILK COMPANY, INC., OF NEW YORK, N. Y., A CORPORATION OF NEW YORK

FABRIC DISPLAY DEVICE

Application filed January 16, 1932. Serial No. 587,031.

This invention relates to improvements in display devices and has particular reference to a chart for exhibiting samples of fabric.

An object of the invention is to provide an improved chart of simple and practical construction, in which the samples are so mounted that they are visible from both sides of the chart and may be grasped to determine the quality of the fabric.

The above and other objects will appear more clearly from the following detailed description, when taken in connection with the accompanying drawing, which illustrates a preferred embodiment of the inventive idea.

In the drawing—

Figure 1 is a perspective view of the chart in its open position;

Figure 2 is a similar view of the same in its folded position;

Figure 3 is a fragmentary enlarged plan view, partly broken away, illustrating the manner in which the samples are secured to the chart;

Figure 4 is an enlarged section on the line 4—4 of Figure 1; and

Figure 5 is a section on the line 5—5 of Figure 3.

The chart of the present invention, which is particularly applicable for displaying samples of fabric, is in the form of a folder comprising a base sheet 6 of any suitable material, such as light cardboard, the end portions of which constitute cover sections 7. The intermediate portion of the sheet is creased at 8 to provide a folding line and divide said portions into display sections 9, each of which is formed with rows of rectangular openings 10.

In assembling the elements of the chart, a plurality of fabric samples 11 of different colors are mounted upon the base sheet 6 with one of said samples associated with each of the openings 10. Each fabric sample 11 is of substantially the same area as the opening 10 and, in accordance with the present invention, each sample is arranged relative to its opening so that two of the edges of the former overlap adjacent portions of the sheet 6 contiguous to two of the edges of the opening 10 and are secured to said sheet by a suit-

able adhesive. When in this position the other two edges of the sample are spaced from the adjacent edges of the opening. To complete the chart, a second sheet 12 is superimposed upon each of the sections 9 of the sheet 6 and is provided with rows of openings 13 which align with the openings 10. The sheets 12 are secured to the sections 9 by a suitable adhesive and the inner or adjacent edges of said sheets are spaced apart, as indicated at 14, so as not to overlap the folding line 8, thereby permitting of a free movement of the sections 9 about said folding line when the chart is opened and closed.

From the foregoing description, it will be seen that a portion of the edge of each sample 11 is interposed between the sheets 6 and 12 in such a manner as to securely hold the sample in position within the confines of the openings 10 and 13 and that the remaining edge portions of the sample will be free from the adjacent edges of said openings. It will further be seen from this construction that the samples 11 will be visible from both sides of the chart and that, by reason of the fact that edge portions of each sample are unattached to the sheets 6 and 12, said sample may be grasped from either side of the chart to enable a person to feel the quality of the sample.

What is claimed is:

1. A display device for fabrics, comprising a mounting having an opening therein, and a fabric sample of substantially the size and shape of said opening and disposed within the confines thereof so as to be visible from both sides of the mounting, a sufficient portion of the edge of said sample being secured to said mounting to normally maintain the sample in the plane of said opening, and the remaining portion being unattached to said mounting.

2. A display device for fabrics, comprising a mounting consisting of a base sheet having an opening therein, a second sheet superimposed upon said base sheet and having an opening aligned with the first-named opening, and a fabric sample of substantially the size and shape of said openings and disposed within the confines thereof, said

sample having a sufficient portion of its edge secured between said sheets to normally maintain the sample in the plane of said openings, the remaining portion of said edge of the 5 sample being free of said sheets.

3. A display device for fabrics, comprising a mounting consisting of a base sheet having a rectangular opening therein, a second sheet superimposed upon said base sheet and 10 also having a rectangular opening aligned with the first-named opening, and a fabric sample of substantially the size and shape of said aligned openings and having two adjacent edges secured between said sheets with 15 the remainder of the sample disposed within the confines of said openings, the two remaining edges of said sample being spaced from the adjacent edges of the openings.

In testimony whereof, I have affixed my 20 signature.

HUGH DONNELL.
